Lacy H. Hancy, Attorney

UNITED STATES PATENT OFFICE.

BENJAMIN C. CROWLEY, OF DILLON, MONTANA.

WIND DEFLECTOR.

Application filed December 19, 1922. Serial No. 607,892.

To all whom it may concern:

Be it known that I, BENJAMIN C. CROWLEY, a citizen of the United States, residing at Dillon, in the county of Beaverhead and 5 State of Montana, have invented certain new and useful Improvements in Wind Deflectors, of which the following is a specification.

This invention relates to means for preventing the accumulation of snow or sand on railroad tracks. Where railroad tracks are laid beside an embankment or extend between two embankments, and the line of extent of the tracks is, generally speaking, 10 transverse to the direction in which the wind will ordinarily blow in the locality in which the tracks are laid, snow or sand will be blown onto the tracks and will accumulate in drifts. Where such drifts accumulate, 15 it is necessary to spend time and labor in removing them to clear the way for the rolling stock. Therefore, it is the primary object of the present invention to devise means whereby the wind currents may be 20 deflected in such a manner as to sweep across the tracks and thus prevent accumulation of snow or sand rather than cause such accumulations. Therefore, the present invention contemplates the utilization of the 25 agency which naturally creates snow and sand drifts under the conditions stated, to serve, in preference, as a medium for preventing the formation of these drifts.

Another object of the invention is to provide, for the purpose stated, a means which will be operative at all times after having been once installed and which will embody no moving parts liable to become disarranged and require attention and repair.

40 In the accompanying drawings:

Figure 1 is a perspective view illustrating the structure embodying the invention installed beside a track which track extends beside an embankment;

45 Fig. 2 is a detail view partly in rear elevation and partly in vertical section illustrating a portion of the structure;

Fig. 3 is a vertical sectional view taken substantially on the line 3-3 of Fig. 2;

50 Fig. 4 is a detail transverse sectional view taken substantially on the line 4-4 of Fig. 2 looking in the direction indicated by the arrows;

55 Fig. 5 is a view similar to Fig. 1 illustrating the manner in which the structure is in-

stalled where the tracks to be cleared are located between two embankments or extend through a cut.

Generally speaking, the structure embodying the invention comprises a wind deflecting surface or shed which is supported in inclined position by a suitable underframe structure, the disposition of the deflecting surface being such that the wind currents striking the underside of the same will be deflected downwardly to sweep over and across the tracks and thus blow from the tracks any snow or sand which would otherwise be liable to accumulate in drifts thereon.

In the drawings the deflecting surface is indicated in general by the numeral 1 and the same is preferably made up of a number of sheet metal plates 2 of any desired dimensions. These plates may, for example, be made of galvanized iron of any suitable gage, or they may be made of sheet iron and painted or otherwise treated to protect them from rusting and deterioration. The plates are disposed with their lateral edges in mutually overlapped relation as indicated by the numeral 3 and the overlapped margins of the plates are permanently secured together by rivets or other fastening elements 4 which are secured therethrough.

These fastening elements are also secured through one wing of angle bars 5 disposed beneath the surface 1 and extending throughout the length of the overlapped margins of the plates 2. These angle bars, of course, serve as a reinforcing means for the plates at their lines of union, and it is also desirable to further reinforce the plates at this point and also prevent their buckling or similar distortion, by disposing upon the upper side of the deflecting surface 1, immediately above and coextensive with the angle bars 5, strips 6 of bar metal or the like which are secured in place by the rivets 4 as shown clearly in Fig. 4 of the drawings. To further reinforce the plates 2 comprising the deflecting surface 1 and particularly to brace and prevent the buckling of the end edges of these plates, angle bars 7 are disposed upon the upper side of the assemblage of plates and extend along the upper and lower margins of the deflecting surface as a whole.

The under frame structure which supports the deflecting surface comprises two series of supporting uprights, one series to be located in a more or less elevated position as,

for example, at the top of the embankment, and the other series to be located at a lower elevation, as, for example, at the bottom of the embankment. Structurally the two 5 series are identical and each upright, which is indicated by the numeral 8, comprises a flat-sided bar 9 anchored at its lower end in a concrete or other base 10 which is to be in turn anchored or embedded in the 10 ground. At their upper ends, the uprights 8 are riveted or otherwise secured as at 11 to the depending wings of certain of the angle bars 5, the uprights being arranged at 15 suitably spaced intervals and being so positioned that they will be edgewise to the wind when the wind is blowing from the usual direction in the locality in which the structure is erected. At this point it will be observed, and particularly by reference to 20 Figs. 1, 3 and 5 thereof, that where the tracks, which are indicated in general by the reference letter "T", extend beside an embankment, indicated by the reference letter "E", one series of the uprights, will, as 25 previously stated, be arranged at the top or brow of the embankment and the other series of uprights will be located at the bottom of the embankment, the two series extending parallel to each other and likewise 30 parallel to the track "T", and while the uprights are disposed perpendicularly, the deflecting surface which they support at their upper ends, will be inclined substantially 35 parallel to the side of the embankment.

40 As the deflecting surface receives the force of the wind currents, it is, of course, desirable to so brace the under frame structure as to counteract this force and prevent any distortion of the surface and this is preferably accomplished by providing diagonal brace bars 12 which are secured at one end to the uprights 8 of the upper series at or adjacent the lower ends of the uprights and at their other ends are secured to the lower 45 series of uprights near the upper ends thereof.

50 It is also desirable to relatively brace adjacent ones of the uprights of each series and this is accomplished through the medium of tie-rods 13 which are arranged in pairs in crossed relation between each two of the uprights of each series and have their upper and lower ends engaged in notches or openings 14 provided in attaching brackets 15 secured to the bars 9 comprising the uprights 8 near the upper and lower ends thereof. Each of the brackets 15 comprises an attaching plate 16 having an end portion 17 turned back at an acute angle and formed 55 with the notch or opening 14 previously referred to. The ends of the tie-rods 13 may be threaded as indicated by the numeral 18 and nuts 19 are fitted onto said ends and may be tightened to bind against the inner 60 faces of the end portions 17 of the attaching 65

brackets so as to impose longitudinal stress on the tie-rods and thus firmly brace the uprights between which they extend.

In the embodiment illustrated in Fig. 1 of the drawings the tracks extend beside an 70 embankment, and a single one of the structures is arranged upon the embankment with the result that when the wind is blowing from the usual direction, snow or sand which would ordinarily accumulate in drifts upon the track "T" will be blown clear of the 75 tracks because of the deflection of the wind currents when they strike the underside of the deflecting surface 1, in a downward direction and across the tracks. Under the 80 conditions illustrated in Fig. 5 of the drawings the track extends between two embankments or through a cut, and in this instance two of the structures are provided, one upon each embankment. With this arrangement, the track will be swept clear by 85 the wind currents whether they be blowing from one direction or the other and it will be evident by reference to the said figure, that while the wind currents after being deflected by one of the structures, will be directed toward the other structure, the last-mentioned structure will not offer any resistance to the currents nor interfere with 90 them sweeping over the track surface, inasmuch as the currents will rise after passing over the track and will pass beneath the 95 deflecting surface of the last-mentioned structure.

100 While the structure is illustrated and described as erected in juxtaposition to a railroad track, it will be understood that the principles of the invention might equally well find embodiment in conjunction with thoroughfares, trails, highways, or, in fact, 105 any place where it is desired to prevent the drifting and accumulation of snow, sand, ashes, or any other material.

110 Under some conditions it may be found desirable to employ a baffle wall in connection with the structure as previously described, as, for example, where the wind may at times blow from a direction more or less inclining toward the line of extent of the structure, and such a baffle wall is illustrated 115 in Fig. 5 of the drawings and is indicated by the numeral 20. In employing such a wall, the wind currents striking the same will be deflected so as to blow or pass in substantially a direction transversely across the track, roadway, or the like to be kept 120 clear.

125 The deflecting surface is illustrated in the drawings as supported by two series of the uprights 8 but it will be evident that three or more such series may be provided if the surface is required to be of such large area as to necessitate this additional support. Also it will be understood that while the structure is preferably of metal, the de- 130

fecting surface, and in fact other parts thereof, may be made of wood if found expedient.

Having thus described the invention, what is claimed as new is:

- 5 1. Means for preventing the accumulation of snow or sand upon a thoroughfare comprising spaced series of uprights arranged one relatively adjacent the thoroughfare and the other more remote therefrom, the last-mentioned uprights extending to a greater elevation than the first-mentioned uprights, bracing bars extending between the upper portions of the first-mentioned uprights and 10 the lower portions of the last-mentioned uprights and relatively bracing the uprights of the two series, and a wind deflecting surface supported upon the upper ends of the uprights in inclined position with relation to 15 the surface of the thoroughfare.
- 20 2. In a structure of the class described, spaced series of parallel uprights, angle bars extending between the upper ends of the uprights in one series and the upper ends of corresponding uprights in the other series, a deflecting surface comprising sheets resting flat upon the frame structure thus pro-

vided and secured to said angle bars and a deflecting member secured to corresponding uprights below the said deflecting surface 30 and arranged transversely to the series of uprights.

3. In a structure of the class described, spaced series of uprights, angle bars extending between the upper ends of corresponding 35 ones of the uprights in the series, and a deflecting surface comprising metallic sheets disposed upon the frame structure thus provided and secured to said angle bars, the sheets being arranged with their margins 40 overlapped, and strips secured over the overlapped margins of the sheets and extending above the angle bars.

4. In a structure of the class described, spaced series of uprights, bracket members fixed to the opposite sides of the uprights and their upper and lower end portions, tie-rods fitted at their ends through the brackets, nuts upon the ends of the tie-rods binding against the brackets, and a wind deflecting surface supported upon the uprights in 45 inclined position.

In testimony whereof I affix my signature.
BENJAMIN C. CROWLEY. [L.S.]
